US00D791933S

(12) **United States Design Patent** (10) **Patent No.:** **US D791,933 S**
(45) **Date of Patent:** ** *Jul. 11, 2017

(54) **COSMETIC DEVICE**

(71) Applicant: **The Procter & Gamble Company**,
Cincinnati, OH (US)

(72) Inventors: **Thomas Elliott Rabe**, Baltimore, MD
(US); **Faiz Feisal Sherman**, Mason,
OH (US)

(73) Assignee: **The Procter & Gamble Company**,
Cincinnati, OH (US)

(*) Notice: This patent is subject to a terminal disclaimer.

(**) Term: **14 Years**

(21) Appl. No.: **29/506,847**

(22) Filed: **Oct. 21, 2014**

Related U.S. Application Data

(63) Continuation of application No. 29/493,364, filed on
Jun. 9, 2014.

(57) **CLAIM**

The ornamental design for a cosmetic device, as shown and described.

DESCRIPTION

FIG. 1 is a bottom view of a cosmetic device, showing our new design;

FIG. 2 is a front view thereof;

FIG. 3 is a first side view thereof;

FIG. 4 is a second side view thereof;

FIG. 5 is a back view thereof;

FIG. 6 is a top view thereof; and,

FIG. 7 is a perspective view thereof.

The broken lines immediately adjacent the claimed areas represent the bounds of the claimed design while all other broken lines are directed to environment and are for illustrative purposes only; the broken lines form no part of the claimed design.

1 Claim, 4 Drawing Sheets
